CONTAINER

Conrad Hofmann, Opladen, and Alex Kneip,
Frankfort-on-the-Main, Germany, assignors to
Winthrop Chemical Company, Inc., New York,
N. Y., a corporation of New York

Application March 29, 1935, Serial No. 13,738
In Germany April 10, 1934

2 Claims. (Cl. 215—37)

The present invention relates to containers.

Glass vessels, bottles and other containers are generally closed by means of stoppers or capsules, while ampoules are usually closed by fusion. Both methods of closing are associated with certain drawbacks. For instance, the fusion of ampoules which contain combustible substances is extremely dangerous, while stoppers or capsules frequently provide an insufficiently tight closure; more especially is this so when the materials used for closing the containers undergo chemical or physical changes (for example contraction) owing to the action of the substances contained by the vessels.

An improved closure is provided by the invention according to which an ampoule, a glass vessel or other container having a neck is closed by means of a seal consisting of a body, which partly seals the vessel, and another body which tightly seals it. Tubular vessels having no neck are also sealed in the same manner.

The invention is carried out in one manner by forming a contraction in the neck of a vessel or the end of the tube, the contraction being such as to provide in the neck or tube end a seating surface for a closing body which is then loosely placed thereon. This body may, for example, be spherical. The open part of the neck or tube end above the loosely inserted body is then closed by an inert liquid or plastic material which subsequently hardens and tightly closes the vessel, examples of such materials being molten metals, amalgams and cements.

Suitable materials for tightly closing the vessels are the alloys known by the names Wood's metal and Rose metal, and amalgams of these alloys having a mercury content of about 5 to 10 per cent; other materials are water-glass cements, cements of lead oxide and glycerine and fused resins.

The neck or tube end is not necessarily contracted and in such case there may be used wadding or glass wool as the loosely closing body which serves to support the tightly closing material.

The invention is illustrated by the accompanying drawing, in which:

Fig. 1 shows the neck of an ampoule contracted at 1 with a ball 2 resting on the contracted part.

Fig. 2 shows a complete ampoule with a contracted neck and closed by a ball 2.

Fig. 3 shows the same ampoule shown in Fig. 2 with the neck above the ball 2 closed tightly by a material 4. The ampoule thus sealed may be opened by breaking off the neck which is scratched for this purpose by means of a file at the contraction 1 or at the line 3.

Fig. 4 shows the neck of an ampoule which has not been formed with a contraction and which contains wadding or glass wool 5 as a loosely closing body below the tightly closing material 4.

We claim:

1. A sealed package comprising a container having a neck; a loosely fitting non-sealing body within and at a substantial distance from the outer extremity of the neck; and within the neck and filling the space therein outwardly of the coarsely fitting closing body for a distance sufficient to provide a plug, a body of an alloy containing lead, bismuth and tin which expands upon solidification, the latter body combining with the inner surface of the container neck to provide a non-removable seal of the container.

2. A sealed package comprising a container having a neck; a contraction in said neck at a substantial distance from the outer extremity of the latter; in the neck and adjacent but outwardly disposed with respect to said contraction a spherical coarsely fitting non-sealing closing body having a diameter intermediate that of the neck and that of the contraction; and, within the neck and filling the space therein outwardly of the coarsely fitting closing body for a distance sufficient to form a plug, a body of an alloy containing lead, bismuth and tin which expands upon solidification, the latter body combining with the inner surface of the container neck to provide a permanent and non-removable seal of the container.

CONRAD HOFMANN. 45
ALEX KNEIP.
